United States Patent Office.

MARY E. PARSONS, OF HILLSDALE, MICHIGAN, ADMINISTRATRIX OF THE
ESTATE OF MILO J. PARSONS, DECEASED.

Letters Patent No. 61,858, dated February 5, 1867.

IMPROVED WASHING MACHINE.

The Schedule referred to in these Letters Patent and making part of the same.

TO ALL WHOM IT MAY CONCERN:

Be it known that MILO J. PARSONS, deceased, late of Hillsdale, Hillsdale county, Michigan, did during his lifetime invent a new and useful Improvement in Washing Machine; and I, MARY E. PARSONS, of Hillsdale, as aforesaid, administratrix of the estate of said MILO J. PARSONS, deceased, do hereby declare that the following is a full, clear, and exact description thereof, which will enable those skilled in the art to make and use the same, reference being had to the accompanying drawing, forming part of this specification, in which—

Figure 1 is a longitudinal section of my improved washing machine, taken through the line *x x*, fig. 2.

Figure 2 is a vertical cross-section of the same, taken through the line *y y*, fig. 1.

Similar letters of reference indicate corresponding parts.

My invention consists in the combination and arrangement of the crowned springs, flat springs or bars, and standards, by means of which the rollers are suspended and held up against the stationary revolving cylinder in such a way that they can adjust themselves to the varying thickness of the clothes passing between them and the said cylinder.

A is the box or tub of the machine, which may be made of any desired shape or size, and which is supported upon legs, *B*, so as to be at a convenient height. The bottom *a'* of the box *A* is made of zinc, and has its middle part curved downward, as shown in fig. 1, to form a depression for the reception of the rollers, so that the clothes may more readily enter between them and the stationary fluted cylinder, beneath which they are suspended. *C* is a cylinder, the surface of which is fluted longitudinally, as shown in the drawings. The journals of the cylinder *C* revolve in bearings at the bottom of vertical slots, formed in the sides of the box or tub *A*, as shown in fig. 2 and in dotted lines in fig. 1. *D* is the crank, attached to the projecting end of one of the journals of the cylinder *C*, by means of which the machine is operated. *E* are flat springs or bars, which rest upon the upper edges of the sides of tub *A*, and are secured at their centres to small blocks, *F*, which fit into the vertical slots formed in the sides of the said tub, and form the upper or removable parts of the bearings for the journals of the cylinder *C*. The ends of the bars *E* are secured in place by the loops *G*, which are pivoted to the projecting ends of the side boards of the tub *A*, and are slipped over the ends of said bars, as shown in fig. 1. Near the ends of the bars *E* are formed slots to receive tongues formed upon the ends of the crowned springs *H*. The springs *H* are curved, as shown in fig. 1, and upon their ends are formed tenons or tongues that enter the slots in the bars *E*, so that their ends may move back and forth as the pressure upon the springs *H* varies. *I* are blocks, resting upon the middle parts of the springs *H*, and to which the standards *J* are securely attached. The upper ends of the standards *J* are kept in their proper relative positions by the cross-bar *K*, as shown in fig. 2. The middle parts of the standards *J* are slotted, as shown in fig. 2, for the passage of the journals of the cylinder *C*, so that the said standards may move up and down independently of said cylinder. *L* are rollers, pivoted to the lower parts of the standards *J* in such positions as to correspond with the curve of the cylinder *C*, as shown in fig. 1. *M* are narrow aprons, attached to the lower ends of the standards *J*, as shown in fig. 1, to facilitate the introduction of the clothes between the rollers *L* and fluted cylinder *C*. By this construction the rollers *L* are enabled to adjust themselves to the thickness of clothes between them and the cylinder *C*, by compressing the springs *H*. It will be observed that by turning down the loops *G*, the rollers, cylinder standards, springs, and bars may all be removed from the tub *A*.

I claim as new, and desire to secure by Letters Patent—

The combination and arrangement of the crowned or curved springs *H*, the bars or springs *E*, and standards *J* with each other, and with the box or tub *A* and cylinder *C*, substantially as herein shown and described.

MARY E. PARSONS,
Administratrix of the Estate of Milo J. Parsons, deceased.
